UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

PROCESS OF FRACTIONING BROMIN FROM CHLORIN.

SPECIFICATION forming part of Letters Patent No. 752,331, dated February 16, 1904.

Application filed May 21, 1903. Serial No. 158,077. (No specimens.)

To all whom it may concern:

Be it known that I, HERBERT H. Dow, a citizen of the United States, and a resident of Midland, county of Midland, and State of Michigan, have invented a new and useful Improvement in Processes of Fractioning Bromin Apart from Chlorin, of which the following is a specification, the principle of the invention being herein explained and the best mode in which I have contemplated applying that principle, so as to distinguish it from other inventions.

My invention consists of an improved process for fractioning bromin apart from chlorin, and thus obtaining a mixture of bromin and chlorin in which the proportion of bromin to chlorin may be any that is desired up to a practical limit, the production of a mixture in which the amount of chlorin shall be small in comparison with the amount of bromin being especially sought. Said process consists of a series of steps hereinafter fully described.

The annexed drawing and the following description set forth in detail one mode of carrying out the invention, such disclosed means constituting but one of various ways in which the principle of the invention may be used.

In said annexed drawing is represented a diagrammatic view of a form of apparatus used in my improved process.

My improved process is a radical departure in the methods of fractioning apart bromin and chlorin, which are obtained by the oxidation of natural brines, in that heretofore this separation has been accomplished by chemical processes and depended upon the fact that chlorin will liberate bromin from bromids, while in this process the method is purely mechanical and depends upon the fact that the bromin in a brine solution is more volatile than the chlorin formed in the solution at the same time. I have found that when a natural brine is oxidized sufficiently to set free practically all the contained bromin and air is blown through the bromin thus set free the first portions of air escaping from the bromin solution will carry the purest bromin and later portions of air will carry a very impure bromin, the impurity in both

cases being chlorin or a volatile compound of chlorin or a combination of the two, some or 50 all of which are produced in quite a large quantity when the brine is oxidized to its complete bromin content.

Although the method of fractioning bromin apart from chlorin is a radical departure from 55 the methods heretofore used and especially from that described and claimed in my United States Letters Patent No. 714,160, the apparatus used in this process is nearly identical with that used in said Letters Patent, differing 60 only in these respects: Auxiliary oxidizer M and its connections, the connection through the blower F between the absorption-towers L and the blow-out towers C, which are shown and described in the view accompanying the 65 patented process, are omitted in this improvement. There is an air-inlet c provided for the blow-out tower C in this process that is not provided in the patented process. Also in this process the connection c' leads from 70 the blow-out towers C to the blow-out towers N instead of from the towers C to the auxiliary oxidizer M. The rest of the apparatus both in the main and auxiliary systems performs the same functions in this process as those 75 disclosed in the patent, and I shall therefore describe neither them nor their functions more in detail, the lettering being identical in both.

My improved process is carried on as follows: Raw brine from the reservoir R is first allowed to pass through the absorber Q, where it takes up more or less bromin and chlorin and passes on to the reservoir A through the connection a. From here it passes through 80 duct b to the oxidizer B, where by any of the means explained in my reissued Letters Patent No. 11,232 it is oxidized, the oxidation being carried to a point where substantially 85 all the bromin content is set free, more or less chlorin incidentally and of necessity being simultaneously set free. From the oxidizer the brine carrying all the dissolved bromin in the free state passes through duct c' to the blow-out towers C. Here a limited amount of air 90 is allowed to enter through the inlet c, and a

part of the bromin, which is the purest, is carried with a relatively small amount of chlorin into the purifiers E through the pipe G, thence through the pipe H, purifiers J, in which a 5 strong bromid solution (provided from a suitable source, such as the receptacle X) is caused to circulate where the last trace of chlorin is removed by the substitution of such chlorin for the bromin in the bromid solution, thence 10 through pipe K, and to the absorption-tower L, which may contain any suitable material, such as sodium carbonate, (the latter being provided from a suitable source of supply, such as the receptacle Y,) which will combine 15 with the bromin exactly as described in Letters Patent No. 714,160.

As has been mentioned above, the bromin in a brine solution is more volatile than the chlorin in the solution formed at the same 20 time, and by this blowing of the brine with a limited amount of air a mixture of bromin and chlorin is obtained in which the proportion of bromin to chlorin is much higher than the average proportion of the solution and a far 25 purer bromin product obtained than when a large amount of air is used or when limited amounts of air are used successively. The proportion of bromin carried away to the air used also increases with the decrease in the 30 amount of air used. The brine in the towers C still contains a large amount of free halogens, and from it considerable quantities of a less pure bromin may be obtained. The brine is hence conducted through the pipe c' to the 35 blow-out towers N, where it is brought into contact with a large amount of air and all the dissolved free halogens blown out, whence they are carried through the duct O to the absorption-towers Q and are taken up by and serve 40 to oxidize the fresh brine coming down from the reservoir R into the towers Q through duct q'. During the passage of the different solutions through the various parts of the apparatus pumps n, q, j, l, and c' at the bases of the 45 systems of towers N, Q, E, J, L, and C, respectively, serve to convey the various solutions contained or flowing through said systems of towers successively to the one, two, three, or any number of towers comprising 50 each of the respective systems. I shall call a series of blow-out towers, such as C and N, hereinafter an "air system," meaning thereby a tower or plurality of towers connected together for blowing out by means of air a 55 part of the bromin.

As the exact control of the amount of oxidation that takes place is very important in order to get a maximum yield of bromin of the greatest purity consistent with a high extraction, it has become very important that this 60 part of the process should be simplified. It is for this reason that in the improved process herewith described I have dispensed with one of the two oxidizers used in my process, as described in Letters Patent No. 714,160. The

process is further simplified by reason of the fact that a slight excess of oxidation in the process herein described is not as detrimental to the final product as would be in case my patented process was employed.

The large amount of bromin blown out in the air system C compared with the amount of air used makes it possible to more completely remove the chlorin in a limited number of purifying-towers than where the bromin is highly diluted with air, and yet leave the bromin sufficiently pure for the production of commercial bromids.

It will be noted that by controlling the amount of air allowed to enter the air system 80 C bromin of any desired purity up to the practical limit of purity may be obtained and that the proportion of bromin to chlorin in the mixture thus blown out may be as large 85 or small as desired, and, furthermore, bromin may be recovered in any desirable quantity in the said air system C, the remainder, an amount as great as is desired, being allowed to be carried by the brine to the second air system N.

I claim—

1. The steps in the process of fractioning bromin apart from chlorin which consist, in oxidizing bromid-containing brine to excess of its bromin content before removing any of the bromin, obtaining substantially pure bromin by passing through the oxidized brine a limited amount of air, and then recovering the bromin from the bromin-laden air in a suitable absorbent.

2. The steps in the process of fractioning bromin apart from chlorin which consist, in oxidizing bromid-containing brine to excess of its bromin content before removing any of the bromin, and then obtaining bromin and chlorin in the form of gaseous mixtures of varying proportions by passing through the oxidized brine, first, a limited amount of air, and, then, a large amount of air.

3. The steps in the process of fractioning bromin apart from chlorin which consist, in oxidizing bromid-containing brine to excess of its bromin content before removing any of the bromin, and then obtaining bromin of a graduated degree of purity, by passing through the oxidized brine a limited amount of air, thereby carrying off the bromin most pure, taking up this pure bromin in a suitable absorbent, passing a large amount of air through the brine, and then taking up the impure bromin, thus blown out, in a natural brine.

4. The steps in the process of fractioning bromin apart from chlorin which consist, in oxidizing bromid-containing brine to excess of its bromin content before removing any of the bromin, and then obtaining bromin of a graduated degree of purity, by passing through the oxidized brine a limited amount of air, thereby carrying off the bromin most pure, taking up this pure bromin in sodium carbon-

ate, passing a large amount of air through the brine, and then taking up the impure bromin, thus blown out, in a natural brine.

5. The steps in the process of fractioning bromin apart from chlorin which consist, in oxidizing bromid-containing brine to excess of its bromin content before removing any of the bromin, and then obtaining bromin of a graduated degree of purity, by passing through 10 the oxidized brine a limited amount of air, thereby carrying off the bromin most pure,

taking up this pure bromin in a suitable absorbent, passing a large amount of air through the brine without further oxidation, and then taking up the impure bromin, thus blown out, 15 in a natural brine.

Signed by me this 19th day of May, 1903.

HERBERT H. DOW.
